CAR SEAT

Alfred B. Bell, Gardner, Mass., assignor to Heywood-Wakefield Company, Boston, Mass., a corporation of Massachusetts

Application November 7, 1934, Serial No. 751,847

6 Claims. (Cl. 155—96)

This invention relates to reversible seats of the rotatable type suitable for railway cars and similar vehicles in which it may be desired to reverse the direction in which the seat faces.

The present tendency in railway equipment is toward lightness of weight and economy of space. To this end it is desirable that the seats for a railway car be as lightly and simply constructed as is consistent with requisite strength for the 10 comparatively severe usage to which they are customarily subjected. In railway cars, the seats are customarily arranged so that one end is adjacent to a side wall of the car. In seats of the rotating reversible type, provision must be made 15 to enable the corners of the seat to clear the wall as the seat turns. It is desirable that the end of the seat be closely adjacent to the car wall when the seat is in either position of use so that waste space between the seat and the wall may be avoided and the aisle may have maximum width. 20 The corners of the seat may be made to clear the car wall as the seat turns, by the provision of mechanism such that the seat frame shifts away from the wall during the initial portion of the 25 rotation from one position of use to the other, and shifts back toward the car wall during the final portion of such rotation. Since the backs of seats are customarily sloped rearwardly, it is desirable that the back be tilted forward during 30 the initial portion of the rotation of the seat so that its upper corners will clear the backs of adjacent seats on the same side of the car.

According to the present invention, improved mechanism has been provided for accomplishing these results, namely, the endwise shift of the seat away from the wall during the initial portion of its rotation and back toward the wall during the final portion of its rotation, and the automatic forward tilting of the back of the seat during the initial part of the rotation, the seat back returning to its normal angle of inclination during the final portion of the rotation of the seat. My improved structure is relatively simple, is light in weight, but is strong and rugged. The 45 weight of the seat and back is furthermore utilized in a novel manner to maintain the seat firmly in either of its positions of use. Additional means is also provided for holding the seat against any looseness or rocking in any direction when it is in either of its positions of use.

Various additional advantageous features and details will be apparent to one skilled in the art 50 from the disclosure of an embodiment of the

invention in the following description, and on the accompanying drawings of which

Figure 1 is a front elevation of a car chair embodying the invention.

Figure 2 is an end elevation of the same.

Figure 3 is a sectional view on the line 3—3 of Figure 2.

Figure 4 is similar to Figure 3, the movable members being shown in a different position.

Figure 5 is a front elevation similar to Figure 1, 10 but showing a central supporting pedestal.

Figure 6 is a section on the line 6—6 of Figure 3.

Figure 7 is a section on the line 7—7 of Figure 6.

Figure 8 is a sectional view similar to Figure 7, showing the seat swung half-way around.

Figure 9 is a fragmentary section of the seat pivot, this section being taken on the line 9—9 of Figure 7.

Figure 10 is a fragmentary perspective view of one of the hold-down devices.

It is evident from Figures 1 and 5 that one important advantage of mechanism embodying the present invention is that it requires relatively little 25 vertical height, so that if, as shown in Figure 1, the car wall be provided with a support 15 for one end of the seat and a pedestal 16 be provided under the aisle end of the seat, considerable space is left under the seat for the storage of hand baggage. If preferred, a central pedestal 17 may be provided, as illustrated in Figure 5, which is independent of the car wall. Whether the bracket 15 and the pedestal 16 or a central pedestal 17 be employed, a stationary frame may be mounted 35 thereon to support the seat pivot. As shown, this frame may consist of a pair of frame members such as T-irons 20 suitably secured to the supporting pedestal. Permanently secured to these frame members is a horizontal plate 22 40 which holds the members in suitable fixed spaced relation, and stiffens the stationary frame as a whole. A movable seat-supporting frame 25 is hinged to an intermediate frame 26 as at 28, the 45 hinges being adjacent to the front edge of the seat. As shown in Figures 6 and 7, the seat frame 25 bears directly on the stationary base when the seat is in either position of use. This relieves the intermediate frame 26 of the weight of the seat and its occupants when in use. It is 50 understood that the members of the frame 25, instead of being of bar stock as indicated on the drawings, may be made of tubing to save weight. As shown, the intermediate frame 26 may be constructed in the general form of an A, the apex 55

of which carries a pivot member 30 which projects downwardly through a slot 31 in the plate 22 so that the pivot member can rotate and move laterally in the slot. In order to provide for simultaneous rotation and lateral shifting of the frames 25 and 26, the plate 22 may also be provided with a crescent-shaped cam slot 32 in which rides a cam follower 33 mounted on the cross bar of the A-shaped seat frame 26. As is evident from Figure 3, when the seat frame starts to turn from the position shown in full lines, the pivot 30 immediately starts to move away from the car wall, this resulting in lateral movement of the seat frame itself away from the wall as it turns. The cam follower 33 then travels along the cam slot 32, reaching the opposite end of the slot when the seat reaches its other position of use. The final portion of this motion moves the pivot 30 and the seat frame back toward the car wall.

As indicated especially in Figures 7 and 8, novel means for causing the seat frame 25 to rock forward during the initial portion of the rotation is provided. As shown, a bell crank 40 is pivotally mounted as at 41 on a carrier 42 which is adjustably mounted on the plate 22. The bell crank consists of a long arm 43, preferably having at the end thereof a roller 45, and a shorter arm 46 connected by a link 47 to a collar 50 which is loosely mounted on the pivot member 30. The link 47 may be conveniently formed with a pair of arms 51 which extend about the collar 50 and rock on trunnions 52 projecting from the collar. The link 47 and the short arm 46, being pivotally connected as at 53, form a toggle joint which, as hereinafter explained, is effective in helping to maintain the seat securely in one or the other position of use. The roller 45 bears against the under face of a plate 60 which, as shown in Figures 3 and 4, may be of modified crescent shape so that the roller 45 will engage some portion of its under face during the entire movement of the seat from one position of use to the other. By welding a stiffening bar or tube 61 along the rear edge of the plate 60, relatively thin metal can be used for the plate 60. The plate 60 and tube 61 are a part of the seat frame 25. In order to strengthen the pivot mechanism, a lower plate 62 may be rigidly secured below and parallel to the plate 22 as by suitable frame members 63. A slot 65 is provided in this lower plate directly beneath the slot 31. The pivot member 30 projects through both slots and is slideable therein.

Figure 7 illustrates the position of the parts when the seat is in a position of use. The initial rotation of the seat from a position of use is about the cam follower 33 as a pivot, the central pivot 30 starting lateral movement along the slot 31. As is evident from Figure 7, such lateral movement of the pivot 30 toward the right rocks the bell crank 40 so as to elevate the roller 45. Since this roller constantly bears against the under face of the plate 60 which is a part of the seat frame, the rising of the roller 45 causes the seat frame 25 to tilt upwardly so that the seat back which is rigidly attached to the seat frame 25 thus rocks forward. This rocking movement continues until the pivot 30 reaches its extreme position toward the right as in Figure 8, this position being reached when the seat has been turned to an angle of 90°. The bell crank 40 is so shaped that the long arm 43 is substantially vertical at this stage of rotation of the seat so that the elevation of the roller 45 is at its maximum. Further rotation of the seat results in

movement of the pivot 30 toward the left until it reaches the position shown in Figure 7 and the tiltable seat frame 25 is restored to its original level. The angle of tilt of the seat frame 25 may be augmented, if desired, by shaping the plate 60 as indicated in Figure 7 so that the plate itself acts as a cam having high portions 67 and 68 sloping to a low portion 70 near the midpoint of the plate. It is evident that, as the roller 45 moves from a high portion to the central low portion, the effect is to increase the tilt of the seat frame 25.

It is highly desirable that a car seat in either position of use be firmly held against any wobbling or other loose motions. To this end, I provide a number of hold-down lugs 75 such, for example, as are illustrated in Figure 10. These lugs are securely fastened in fixed position and may be conveniently mounted on the stationary frames 20 as shown. Each lug 75 has an upstanding portion 76 and an overhanging portion 77, the under face of which is engageable by one or another of a number of lugs 80 and 81 which are fixed on the seat frame 25. As shown in Figures 3 and 4, eight such lugs may be provided, these lugs being arranged in pairs projecting in opposite directions from a front-to-rear member of the frame 25. Each pair consists of a lug 80 and a lug 81. To cooperate with the lugs 80 and 81, I preferably provide four fixed hold-down members 75 as indicated in Figures 3 and 4. Since the initial movement of the rotatable portion of the seat is away from the car wall, the hold-down lugs 75 are preferably arranged so that their overhanging portions 77 project in a direction away from the car wall. When the car seat is in one position of use, the four lugs 80 engage under the overhanging portions 77 of the hold-down members 75. When the seat is reversed to its other position of use, the overhanging portions 77 are engaged by the lugs 81. Thus the wear on the lugs is divided, since the lugs 80 are in use half of the time and the lugs 81 are in use the other half of the time. The frame members 84, on which the lugs 80 and 81 are mounted, are adapted to rest solidly on bearing elements when the seat is in either of its positions of use. As shown, the bearing elements may be portions of the fixed frame members 20 on which the hold-down elements 75 are mounted. Thus, when the seat is in a position of use, the frame members 84 are held firmly on the frame members 20 by the engagement of the lugs 80 and 81 with the overhanging elements 77. This effectively prevents any wobbling or rocking movement of the seat frame 25. Since the initial portion of rotative movement of the seat necessarily results in a tilting movement of the seat frame 25, the resultant motion of the seat frame and of the lugs 80 and 81 is an ascending spiral from either position of rest to the midpoint of the turn; and then a descending spiral to the other position of rest. In order not to interfere with the initial and final portions of these spiral movements of the lugs 80 and 81, the overhanging elements 77 have their corners bent up as at 85. These act as cam members to be engaged by the lugs 80 and 81 during the final portion of the descending spiral so as to wedge the frame members 84 tightly against the fixed frame members 20. Thus the seat frame is virtually clamped in position and is rigidly held therein. In order to coordinate the tilting and turning movements so that the hold-down lugs will describe the correct spiral paths to bring them into proper en-

gagement under the bent-up corners 85, the block 42, on which the bell crank 40 is rockably mounted, may be slidably adjustable on the plate 22. An adjusting screw 86 may be threaded through a flange 87 in the block 42 with set-screws 88 to hold the block in adjusted position.

It is evident from Figure 7 that the weight of the seat bears on the bell crank 40 with maximum mechanical advantage when the seat is in a position of use, and that in this position the toggle joint 53 comes as near as it can to alignment of the links 46 and 47. These features of construction result in a firm locking of the seat in position until it is simultaneously lifted and turned manually. In order to assist the lifting and turning of the seat, a compression spring 90 may be mounted on a stem 91 which projects from the collar 58 toward the car wall, this stem passing through a guide member 92 between which and the collar 50 the spring 90 is compressed.

It is evident that many modifications and changes may be made in the details of structure shown and described without departing from the spirit or scope of the invention as defined in the following claims.

I claim:—

1. A reversible car seat comprising a stationary base, including a fixed plate having a longitudinal slot therein, a pivot member horizontally movable in said slot, a bell-crank having a normally horizontal arm and a downwardly projecting arm rockably mounted on said plate, connecting means between said pivot member and said downwardly projecting arm for rocking said bell-crank when said pivot member is moved in its slot, and a seat frame tiltably supported in said base, said frame having an element engaged by the free end of said horizontal arm of the bell-crank whereby movement of the pivot member results in tilting of the seat frame.

2. In a reversible car seat or the like, a stationary base, a tiltable seat frame rotatable from one position of use to a reversed position of use, said frame resting directly on said base when in either position of use, means for causing said frame to shift endwise of said base and to tilt forward when rotated from either position of use, and hold-down means for securing said frame against wobbling when in either position of use, said means including a plurality of spaced overhanging lugs mounted on said base, a corresponding set of lugs on said frame engaging under said overhanging lugs when the seat is in one position of use, and a second set of lugs on said frame engaging said overhanging lugs when the seat is in the reverse position of use.

3. A reversible car seat comprising a stationary base, a tiltable and rotatable seat frame

carried by said base, means for causing the seat frame to shift laterally when rotated, and means responsive to lateral shifting of said seat frame to cause said seat frame to tilt, said last-mentioned means including a lever pivotally mounted on said base, said lever having an arm rockable upwardly against said seat frame and means laterally movable with said seat frame and operatively connected to said lever to rock the same.

4. A reversible car seat comprising a stationary base, a tiltable and rotatable seat frame carried by said base, means for causing said seat frame to shift laterally when rotated, said means including a pivot member connected to said frame and slidably mounted on said base, and means responsive to shifting movement of said frame and pivot member to tilt said frame, said last-mentioned means including a bell-crank pivoted on said base, said bell-crank having one arm bearing against the bottom of said seat frame and another arm operatively connected to said pivot member.

5. A reversible car seat comprising a stationary base, a tiltable and rotatable seat frame carried by said base, means for causing said seat frame to shift laterally when rotated, and means responsive to shifting movement of said seat frame to cause said frame to tilt, said last-named means including a non-plane cam plate mounted on the bottom of the seat frame and an element vertically movable with respect to the base in response to lateral shifting movement of the seat frame and bearing against said cam plate, said cam plate having an inclined surface slidably engaged by said element and shaped to augment the tilting effect of the element on the seat frame.

6. A reversible car seat comprising a stationary base, an intermediate frame rotatable and laterally shiftable on said base, a seat frame hinged to said intermediate frame to rotate and shift therewith and to rock relatively thereto, means for controlling the movements of said intermediate frame including a pivot element laterally slidable on said base from and to a normal position, spring means tending to move said element laterally away from its normal position, means responsive to lateral movement of said element to cause said seat to rock on its hinges, said last-named means including a bell-crank pivotally mounted on said base with a horizontal arm bearing against the bottom of said seat frame and a second arm projecting downwardly and a connecting link between said pivot element and said second arm, and means for adjusting the bell-crank pivot toward or away from said pivot element.

ALFRED B. BELL. 60
